 Delaware

Application June 9, 1937, Serial No. 147,188

5 Claims. (Cl. 62—103)

My invention relates to refrigeration with a system having intermittent periods of refrigeration and it is an object of the invention to provide an improved method and organization which effects improved conditions of humidity and temperature in a refrigerator.

The invention is carried out by evaporation and condensation of water in the presence of air to be cooled. The condensation is carried out by cooling air containing water vapor. The evaporation is carried out by presenting water to air which has been dried by said condensation of water vapor. Intermediate the condensation and evaporation steps in the process there may be freezing and melting of the water to produce a hold-over effect for cooling the air.

The invention, together with the objects and advantages thereof, is set forth with particularity in the following description and accompanying drawings forming a part of this specification and of which:

Fig. 1 is a front view of a refrigerator with the door removed and partly in vertical section illustrating more or less schematically one embodiment of the invention;

Fig. 2 is a vertical section on line 2—2 in Fig. 1 with the refrigerator door in place;

Fig. 3 is a horizontal section on line 3—3 in Fig. 1; and

Fig. 4 is a diagrammatic view of a simple intermittent absorption refrigerating system.

Referring briefly to Fig. 4, an intermittent absorption refrigeration system comprises a generator-absorber 10, a condenser 11, and an evaporator 12. The evaporator 12 is located in a refrigerator storage compartment 13 and is connected to the condenser 11 by a conduit 14. The condenser 11 is connected by a conduit 15 to the generator-absorber 10. The generator-absorber 10 is heated by a suitable heating means such as a gas burner 16. The system contains a suitable refrigerant fluid such as ammonia and a suitable absorbent such as water and is hermetically sealed. The absorbent is contained in the generator-absorber 10. When the heater 16 is turned on, refrigerant vapor is expelled from the absorbent and flows through conduit 15 into the condenser 11. In the condenser, refrigerant vapor is liquefied and the liquid flows into the evaporator 12. This period is variously referred to as a heating period, high pressure period, or generating period. No refrigeration is produced during this period. When the heater 16 is turned off, the generator-absorber 10 cools and absorption of refrigerant vapor into the weakened ab-

sorbent takes place. The resulting lowering of pressure causes evaporation of refrigerant liquid in the evaporator 12, producing a refrigerating effect in the refrigerator compartment 13. This period is variously known as the low pressure period, refrigerating period, or absorption period.

During the low pressure period, the evaporator 12 is at a low temperature. If ice is to be frozen in the refrigerator, the evaporator 12 is operated at a temperature below freezing during the low pressure period. The lowest temperature of the evaporator is obtained during the first part of the low pressure period and the temperature gradually rises until the next low pressure period is reached. It has been proposed to provide a hold-over in connection with the evaporator to cool air in the refrigerator compartment 13 during the high pressure periods. Such holdover may be a brine or alcohol solution to be frozen during the low pressure or refrigerating period. The freezing temperature of a brine or alcohol solution is the highest at the beginning of the low pressure period while the lowest temperature of the evaporator is obtained during the first part of this period. Therefore, a hold-over of this nature gives a more constant cooling, but retards rapid recovery of box temperature at the start of the refrigerating period. In accordance with my invention I make use of the cycling feature rather than try to eliminate the effect.

Referring to Figs. 1, 2, and 3, the evaporator 12 is located in the upper part of a thermally insulated storage compartment 13 of a refrigerator cabinet 17. The evaporator 12 is connected by conduit 14 to a suitable refrigeration system, not shown, having intermittent refrigerating periods as described in connection with Fig. 4. The evaporator 12 has no brine tank or other especially provided hold-over. Below the evaporator 12 is a trough 18 having a downward spout 19. Below the lower end of the spout 19 is a vessel 20 having a slightly peaked top 21 and an upward ledge 22 forming a shallow tray with the top 21. The vessel 20 may be secured in place by any suitable means such as brackets 23. The front end of the vessel 20 is open for access thereto when the refrigerator door 25 is open and adapted to be closed by a gasket 24 on the inside of the refrigerator door 25 when the latter is closed. A plate 26 forms a shallow passage 27 for upward flow of air in the rear of the refrigerator compartment 13 from the space below the bottom of vessel 20 to the upper part of the refrigerator compartment.

During operation of the above described re-

55

frigerator, the evaporator 12 will cease to absorb heat during each high pressure or generating period of the refrigeration apparatus. During this time frost formed on the evaporator 12 during the preceding refrigerating period will cool the air and melt. Melting of ice cubes during this time is usually not appreciable if the ice tray compartments 28 are enclosed. Water formed by melting of frost from the evaporator 12 drips into the trough 18 and flows through the funnel 19 into the shallow tray on the top of the vessel 20. This shallow tray on the top of the vessel 20 covers the entire horizontal area of the refrigerator storage compartment 13 except for 15 passages at the rear and sides for air circulation. During the next low pressure or refrigerating period of the refrigeration apparatus, air flows downward over the evaporator 12 and then over the large surface area of water in the drain tray. 20 Air which is dried in contact with the evaporator 12 is re-humidified by evaporation of water in the drain tray into the dry air.

The closed vessel 20 provides a humid chamber for storage of vegetables and the like. The evaporation of water from the drain tray on the top of vessel 20 causes cooling of this humid compartment. This cooling makes possible a large humid compartment of which the cooling might otherwise be too slow.

30 Circulation of air in the refrigerator compartment 13 is upward at the rear of the compartment through passage 27 and then downward over the evaporator 12 and the wide drain tray. The baffle plates 29, 30 cause the air to flow from the center outward over the drain tray and may also be used as shelves. The evaporator 12 being in the upper part of the compartment 13, flow of air is caused by natural effect of gravity due to cooling of the air by the evaporator.

40 Various changes and modifications may be made within the scope of the invention which is not limited as described in the foregoing part of the specification and the accompanying drawings but only as indicated in the following claims.

45 What is claimed is:

1. In a refrigerator having a thermally insulated compartment and a refrigeration system having intermittent periods of refrigeration and including a cooling element in said compartment, a shallow receptacle located beneath said cooling element and extending over a major portion of the horizontal area of said compartment, said cooling element being located in the upper part of said compartment so that air is caused to flow downward over said cooling element and receptacle by natural effect of gravity due to cooling of air by said cooling element, and water which is melted from said cooling element and collected in said receptacle intermediate the refrigerating periods of said system being evaporated from said receptacle into air dried by said cooling element during the refrigerating periods of said system, and a closed compartment for vegetables or the like in thermal exchange relation with said receptacle for cooling by evaporation of water from said receptacle.

2. In a refrigerator having a thermally insulated compartment and a refrigeration system including a cooling element in said compartment, a shallow receptacle located beneath said cooling element and extending over a major portion of the horizontal area of said compartment, said cooling element being operated at temperatures alternately above and below the freezing point of water, and said cooling element being located in the upper part of said compartment so that air is caused to flow downward over said cooling element and receptacle by natural effect of gravity due to cooling of air by said element, and water which is melted from said cooling element and collected in said receptacle when the temperature of said cooling element is above the freezing temperature of water being evaporated from said receptacle into air dried by said cooling element when the temperature of said element is below the freezing temperature of water, and a closed compartment for vegetables or the like in thermal exchange relation with said receptacle for cooling by evaporation of the water from said receptacle. 15 20

3. A method of refrigeration which includes causing circulation of air within an enclosure to be refrigerated, intermittently cooling said air and causing removal of water from the air by formation of frost, alternately cooling the air by melting of said frost, retaining water in contact with the air over a major portion of the horizontal area of said enclosure and in thermal exchange relation with a second enclosure to humidify air in said first enclosure which is dehydrated during the periods of frost formation and cool air in said second enclosure. 30 35

4. A method of refrigeration which includes causing circulation of air within an enclosure to be refrigerated, intermittently cooling said air and causing removal of water from the air by formation of frost, alternately cooling the air by melting of said frost, and retaining water formed by melting of the frost in contact with the air over a major portion of the horizontal area of said enclosure and in thermal exchange relation with a second enclosure to humidify air in said first 40 45 enclosure which is dehydrated during the periods of frost formation and to cool air in said second enclosure.

5. In a refrigerator having a storage compartment and an intermittent refrigeration system including a cooling element in said compartment, a receptacle for water located beneath said cooling element and extending over a major portion of the horizontal area of said compartment, said cooling element being located in the upper part of said compartment so that air is caused to flow downward over said cooling element and receptacle by natural effect of gravity due to cooling of air by said cooling element, and water in said receptacle being evaporated into air dried by said cooling element during the refrigerating periods of said intermittent system, and a closed compartment for vegetables or the like in thermal exchange relation with said receptacle for cooling by evaporation of water from said receptacle. 50 55 60 65
